EDWARD W. CLARK, OF LOS ANGELES, CALIFORNIA, ASSIGNOR OF ONE-HALF TO
ALVIN WELLS, OF LOS ANGELES, CALIFORNIA.

CYLINDER-GRINDING MECHANISM.

1,281,764.

Specification of Letters Patent. Patented Oct. 15, 1913.

Application filed December 10, 1914. Serial No. 876,497.

To all whom it may concern:

Be it known that I, EDWARD W. CLARK, a citizen of the United States, residing at Los Angeles, in the county of Los Angeles and State of California, have invented certain new and useful Improvements in Cylinder-Grinding Mechanisms, of which the following is a specification.

This invention relates to improvements in grinding and boring mechanisms and has particular relation to a mechanism capable of grinding or boring engine or other cylinders, or shaping, or surfacing the interior of mechanisms or devices.

It is an object of the invention among other things, to provide a portable grinding or boring device which may be placed upon the cylinder or cylinders to be ground or bored, and in the case of an engine of the multiple cylinder type, may be quickly transferred from one cylinder to another for grinding or boring each of said cylinders.

It is also an object of the invention to provide such a portable grinding mechanism with means for quickly and yet accurately centering the grinding mechanism with respect to the cylinder or other device to be operated upon.

It is a further object of the invention to provide a grinding mechanism of the character mentioned in which a tool carrying mandrel may be adjustably carried by a concentrically moving or outer mandrel, whereby the tool carrying mandrel may be set eccentrically for accomplishing the desired range of movement in the tool used for grinding or boring.

It is a still further object of the invention to provide a grinding mechanism with suitable tool carrying mandrels, the same being mounted in an adjustable sleeve or support whereby the mandrels may be set at any desired angle for operation, or at any desired height in the supporting frame of the device.

With these and other objects in view the invention comprises certain novel constructions, combinations and arrangements of parts as will be hereinafter more fully described and claimed.

In the accompanying drawing:

Figure 1 is a side elevation of a grinding and boring mechanism constructed in accordance with the present invention and positioned upon the engine cylinders of an automobile, a portion of one of the cylinders being broken away to show a grinding tool in position therein.

Fig. 2 is a detail sectional view taken through the vertical standard of the frame which carries the grinding tool, and through the stem of the tool, the parts below being shown in plan with the grinding tool located in a cylinder.

Fig. 3 is a detail transverse sectional view taken on the line 3—3 of Fig. 5.

Fig. 4 is a detail vertical sectional view taken upon the line 4—4 of Fig. 6.

Fig. 5 is an end elevation of the grinding mechanism mounted upon the cylinders of an engine as shown in Fig. 1.

Fig. 6 is a top plan view of the mechanism, a portion of the top plate being broken away and also portions of the base plate and the carrier bars mounted thereon.

Fig. 7 is a transverse sectional view upon an enlarged scale taken upon the line 7—7 of Fig. 5.

Fig. 8 is a detail sectional view of the micrometer device carrying the diamond employed in properly setting the grinding tool, said diamond also being used to true up the edges of the tools.

Fig. 9 is a side elevation of a portion of a lathe with the grinding device mounted upon the tool carriage thereof.

Fig. 10 is an enlarged detail sectional view through the mandrels of the grinding device together with the adjacent supporting parts.

Fig. 11 is a detail view partially in elevation and partially in section showing a boring cutter carrying attachment mounted upon the lower end of the outer mandrel.

The mechanism of the present invention is intended to afford a portable means for grinding, boring or shaping devices and more particularly for grinding or boring engine cylinders or parts. The device is well adapted for grinding and boring the cylinders of automobile engines, for it can

be placed upon the cylinders of the engine and quickly adjusted so as to be properly centered for accurately finishing the interior of a cylinder, and can then be readily 5 moved to an adjacent cylinder for grinding or boring it. The mechanism can however be placed upon a lathe if desired for coöperating with the parts thereof for grinding or shaping devices of various kinds. The 10 details and features of the invention will now be more specifically described with reference to the accompanying drawings in which the preferred form of mechanism embodying the invention is disclosed, and in 15 which 10 indicates a base plate, 11 carrier bars adjustably mounted thereon and 12 a sliding member or carriage movably mounted upon the said bars.

Any desired form of base plate may be 20 employed for supporting the carrier bars, but one of the type shown in Fig. 6 is preferable since it is provided with a series of openings 13 usually closely spaced with respect to each other, whereby the plate may 25 be engaged by bolts for clamping it to a cylinder or cylinders, or bolts or securing means may be passed through the openings for securing the holding means used for keeping the carrier bars 11 in place on the 30 said plate. Thus as shown in Figs. 1 and 5 clamping bolts 14 may be employed for clamping the base plate 10 to the flanges of a block of engine cylinders 15.

The carrier bars 11 are preferably held in 35 position on the base plate 10 by means of adjustable holding devices made up of plates 16 having bolts 17 adapted to engage any of the openings 13 for fastening the plates 16 upon said base. Bar supporting blocks 18 having bar receiving sockets 19, rest upon the said plates 16 and are adjustably secured thereon by means of bolts 20 and nuts 21, the said bolts passing through slots 22 whereby the blocks 18 may 45 be adjusted longitudinally. The nuts 21 are generally provided with handles 23 for convenience in operating them and quickly adjusting the carrier bars 11. The plates 16 are also usually provided with upturned end 50 portions 24 carrying adjusting screws 25 which bear on the adjacent ends of the blocks 18 for obtaining a nicer adjustment of the said blocks and the bars 11 carried thereby. The portion of the block 18 in 55 each instance, which engages the bar 11 is usually split at 26 so that it can be drawn tightly upon the bar by clamping bolts 27 after the bar has been properly adjusted. The plates 16 are generally located near the 60 outer corners of the base plate 10 and the bars 11 set therein in approximately the desired position. The said bars may then be adjusted toward or away from each other, or both be shifted toward one edge of the base plate 10 or the other in order to ac-

curately center the grinding or boring tool with respect to a cylinder. Such adjustment is facilitated by the adjusting screws 25, the nuts 21 being loosened temporarily, and tightened after the adjustment. 70

Adjustably mounted upon the bars 11 is the sliding carriage 12 having passages bored therein on each side, to fit upon the bars 11. The ends of the elongated bearings thus formed are usually split for a short 75 distance at their ends as at 28 and bolts 29 are provided for drawing the split portion together after the carriage has been properly adjusted for firmly holding the said carriage in such adjusted position 80 while the boring or grinding operation is progressing. In bringing the carriage with the grinding tool and the operating mechanism therefor over a cylinder, the carriage is slipped longitudinally of the bars 85 11 until approximately in the right position. Adjusting collars 30 and 31 mounted upon the bars 11, one being located on each side of the carriage 12, and one on each bar 11, are slipped against the sleeve or 90 bearing portions of the carriage. Each of said collars carries an adjusting ring which may be termed for convenience, a micrometer ring as 32 and 33, the said rings having peripheral scale markings adapted to be 95 moved with respect to marks or indications 34 and 35 on the ends of the carriage sleeves. Each collar is split and has a clamping bolt as clearly shown in the drawing and when the carriage requires a fine adjustment in 100 either direction, the collar which is to push the carriage in the direction desired is slipped against the carriage sleeve and clamped on the rod 11, after which the micrometer ring is turned until the desired 105 position of the carriage has been attained. If the carriage must be adjusted slightly in the opposite direction, the other collar with its micrometer ring is employed, the first collar having first been loosened sufficiently to permit the necessary returned 110 adjustment of the carriage. By the use of the two collars described, a very accurate adjustment of the carriage with its grinding or boring tools may be had. 115

Arising from the sleeve portions of the carriage 12 are uprights or standards 36, said standards generally being cylindrical in shape and may be formed of rods or bars which are thick enough to possess the necessary rigidity and stiffness for properly holding the tools for accomplishing accurate work. The upper ends of said standards 36 are connected and braced by a top plate or ring 37. The ring formation of said 120 plate permits access to the upper end of the mandrel supported between the standards for adjusting the tool carrying mandrel which operates within it, as will be hereinafter more fully described. 130

The said standards 36 carry a vertically moving carriage made up of sleeves 38 and 39 and a casing 40 arranged between and connecting them. The said sleeves have 5 split end portions like the sleeves of the carriage 12, said split portions having bolts 41 for causing them to bind upon the standards 36 and grip them after the said sleeves have been vertically adjusted. The said sleeves 10 are provided with oppositely arranged disk portions 42, the inner faces of which bear against correspondingly shaped portions upon the casing 40. Projecting from the central portions of the disks 42 are trunnions 43 which engage corresponding recesses 44 in the casing 40. The casing 40 carrying the operating tools may thus be turned between the disk portions 42 of the sleeves 38 and 39 so as to extend vertically 15 between the standards 36, or horizontally with respect thereto or at any inclined angle with respect to said standards that may be needed for accomplishing work of any kind. The edge of one of the disk portions 42 may be provided with scale graduations 45 adapted to be moved with respect to an arrow or other indicating mark 46 on the adjacent portion of the casing 40. The parts may be clamped in adjusted position 20 by means of clamping bolts 47, which are threaded in apertures in the said disk portions 42 and have cross heads 48 at their inner ends which engage circular undercut grooves formed in the side faces of the said 25 casing 40, as will be readily understood by reference to Figs. 3 and 10 of the drawing. For convenience in bringing and holding the casing 40 to a perfectly true vertical adjustment a pin 50 may be inserted in 30 registering holes bored through one of the disk portions 42 and in the face of the adjacent portions of the casing 40.

The casing 40 is cylindrically bored to receive an elongated bearing member 51. As 35 the casing is more frequently used in its vertical position, than in any other, the bearing member 51 is generally formed with an annular projection or thickened portion 52 at its upper end which rests upon the 40 upper edge of the casing 40. The said bearing member 51 is elongated so as to extend a considerable distance below the casing 40, and is centrally bored longitudinally thereof to form a bearing for an outer mandrel 53. The upper end of the said mandrel 53 is enlarged so as to extend over the annular projection 52 and is provided with gear teeth forming a worm gear 54 adapted to mesh with a worm 55 mounted to one side 55 of the mandrel. The said worm 55 is rigidly secured to a shaft 56 journaled in bearings 57 and 58 which project upwardly from the upper edge of the casing 40, outside the annular projection 52 and the worm gear 54, as will be clearly understood by reference 60 to Fig. 6 of the drawing. The said shaft 56 is provided with any desired mechanism for driving it, preferably as will be hereinafter more fully described and claimed. The lower end of the mandrel 53 70 is provided with exterior screw threads which are engaged by a ring nut 59 for preventing any longitudinal movement of the mandrel within the bearing member 51.

The ends of the mandrel 53 carry blocks 75 60 and 61, said blocks extending from the end of the mandrel, inwardly a sufficient distance to receive adjusting means for operating the inner or tool carrying mandrel sleeve 62 which extends longitudinally 80 through the said outer mandrel. The blocks 60 and 61 are usually fastened in the ends of the mandrel 53 by set screws 63. The said blocks are each of them provided with elongated openings 64, the ends of which are 85 generally made semi-cylindrical, the inner end of each opening being concentric with the mandrel 53 while the outer ends extend to the peripheral edge of each block so as to have only a thin wall at that point as will 90 be clearly understood by reference to Figs. 3 and 7 of the drawing.

Adjustably mounted in the said openings 64 and extending throughout the length of the outer mandrel and short distances beyond the blocks 60 and 61, is the inner mandrel containing sleeve 62, usually of just sufficient diameter to movably fit in said openings 64. Journalled within the sleeve 62 is a hollow inner mandrel 65, the ends of the 100 said mandrel being held concentrically of the sleeve 62 by means of suitable bushings 66 and 67 which are set in enlarged recesses in the ends of the sleeve 62. The bushings are held in place and protected at the ends 105 of the sleeves in any desired manner, ring caps 68 and 69 being usually screwed on the ends of the sleeve 62, as clearly shown in Fig. 10. The hollow mandrel 65 is provided with a reduced threaded portion 70 110 at its upper end which projects through a central opening in the cap 68 and is engaged by locking ring nuts 71 and 72, said nuts generally having holes in the periphery thereof which may be engaged by spanner 115 tools for adjustment. A grooved pulley 73 is also applied upon the said threaded end portion 70, of the mandrel for rotating the same.

The lower end of the bore in the mandrel 120 65 is enlarged and tapered as at 74 to receive the tapered end of the shank 75 of the grinding tool. A drawbar 76 fits in the remaining portion of the mandrel bore and has a reduced threaded end portion 77 125 adapted to engage a threaded socket in the shank 75 for drawing the same tightly into the tapered socket 74. The upper end of the draw bar 76 is enlarged at 78 so as to have a bearing on the upper end of the mandrel 130

and is also provided with a many sided or hexagonal portion 79 for the application of a wrench or key in turning the said drawbar. The rotation of the mandrel 65 is thus effective for rotating the shank of a tool when the mandrel is driven by suitable belting as hereinafter described.

Inasmuch as it is needful to properly oil or lubricate the outer and inner mandrels, 10 and yet it is desirable to prevent oil from running down upon the grinding tools employed, which tools are usually of emery, carborundum or the like, means is provided for preventing any oil which may work 15 downwardly from the bearings of the mandrels, from reaching the shank of the drill and thereby the tool. For this purpose the lower end of the mandrel 65 is provided with an annular shoulder 80 below which a 20 reduced threaded portion 81 projects as illustrated in Fig. 10. An oil collecting cup 82 is provided with a threaded aperture adapted to engage the reduced threaded portion 81. The outer peripheral portion of said 25 cup is made large enough to extend beyond and around the lower cap ring 69. Sufficient space is left between the ring and the cup to collect the slight drippings of oil that may run down from the mechanism above. The central threaded portion of the 30 cup 82 is screwed tightly against the shoulder 80 to prevent leakage at that point. The cup can be removed from time to time whenever the oil appears to collect therein 35 to any appreciable amount. Emery or other grinding heads or tools do not do well if oil reaches them, as is well known and hence much of the grinding of cylinders, engine rings and other devices is done 40 with the arbors of the tools in horizontal positions to avoid getting oil thereon. By the use of the oil cup just described tools can be operated in vertical positions or inclined positions without the trouble heretofore experienced with the oil. It is especially desirable with a portable device 45 like that of the present invention to be able to do the grinding with vertically held tools, for it is easy to set the device upon engine cylinders as above set forth and especially when operating upon automobile engines of any kind.

The manner in which the inner mandrel is adjusted and positively held forms an 50 important feature of the invention. The said mandrel 46 is adjusted by moving the sleeve 62 toward and away from the axis of the outer mandrel 53. To accomplish this adjustment, parallel oppositely threaded 55 screw rods 83 and 84 are arranged in the upper and lower blocks 60 and 61 respectively. The upper and lower pairs of screw rods are operated in the same manner and a description of the upper pair with reference to Figs. 7 and 10 will suffice for both.

Each of the screw rods is provided with a gear 85 which meshes with a worm 86 secured to a longitudinally extending shaft 87 having bearings in the blocks 60 and 61. The upper end of said shaft is provided 70 with a squared key socket 88 adapted to receive the squared end of a rod or key whereby the shaft 87 may be turned when desired. The socketed end of said shaft 88 projects to the upper surface of the upper 75 block 60 as shown in Fig. 6, so as to be approximately flush therewith whereby the key can be readily inserted at any time for turning the shaft 87 and the worms carried thereby. The blocks 60 and 61 are 80 usually provided with removable blocks 89 which normally close openings through which the screw shafts and their gears may be inserted, when assembling parts of the device. The smooth portions of the screw 85 rods 83 and 84 engage bearings in the said blocks 60 and 61, while the threaded portions pass through cut-away portions of the sleeve 62 and engage threaded apertures in nuts 90 set in recesses formed in the opposite sides of said sleeve 62 will be readily understood by reference to Fig. 7. It will be thus apparent that by turning the shaft 87, the screw rods 83 and 84 may be caused to move the sleeve 62 away from the axis 90 of the outer mandrel, to secure any desired eccentric action in the inner mandrel carried by said sleeve. This structure facilitates the moving of the rotating grinding tool around the inner surface of the cylinder to 100 be ground with somewhat of a gyratory movement as will be readily understood by an examination of Figs. 1 and 2 of the drawing. The grinding tool is kept in rapid rotation by driving the pulley 73 and the 105 periphery of said grinding tool is carried entirely around upon the inner surface of the cylinder by the rotation of the outer mandrel through the agency, of the worm 55 and the gear 54.

The eccentric adjustment of the grinding or boring tool and the inner mandrel carrying the same is of course accommodated to the size of the cylinder to be ground. The accurate setting of a grinding tool is 110 facilitated also by the use of a diamond 91 such as is commonly employed for truing up grinding heads or tools. The mounting of the said diamond 91 and its adjustment is also one of the important features of this invention. The diamond is carried by a rod 92 having a suitable handle 93, the said rod being tapered as shown in Fig. 8 and thus adapted to fit tightly in the tapered bore of a screw 98, which I shall call for convenience 120 a micrometer screw. The said micrometer screw engages a threaded opening 94 in a flange formed on the transverse or bridging portions of the carriage 12 which connects the sleeves upon the rods 11. The microme- 130

ter screw is provided with an adjusting head 95 having scale graduations 96 on the periphery thereof, which are moved by turning the said head, with respect to a scale bar 97 also having scale indications thereon, said bar 97 projecting from the bridging portions of the carriage 12, above and parallel with the micrometer screw 98. The adjustment of the micrometer screw permits the diamond to be set with a very fine adjustment with respect to the cylinder to be ground, it being set just the proper fraction of an inch outside the circumference of the cylinder bore to cause the grinding tool when it has been set up to the diamond 91 and trued by turning it against the same, to cause said grinding tool to take off the desired material from the inner surface of the cylinder. It will be observed that an opening of sufficient size is provided in the transverse bridging portion of the carriage 12 to permit the diamond to be readily seen as well as the bore of the cylinder and the grinding tool, to permit of the setting of the tool for the grinding operation.

Means is also provided for carrying the grinding tool downwardly as it moves around within the cylinder, which is being ground. This means usually consists in a vertical feed screw 100 which engages a threaded aperture formed in the top plate or ring 37 of the device. The lower end of the feed screw 100 has a swivel connection at 101 with one of the sleeves as 38 of the vertically moving tool carriage. The upper end of said screw rod may be provided with a cross handle 102 so that the screw can be fed up and down by hand when desired, as for instance when setting the boring tool. When the grinding operation begins however it is preferable to employ an automatic feed, for steadily feeding the carriage downwardly as required. The lower end of the screw 100 is extended below the swivel connection 101 and is provided with a gear 103, adapted to engage a worm 104 which is brought into mesh therewith at the proper time. The worm 104 is carried by a shaft 105 which is journaled in a bracket 106 secured to the sleeve 38. The shaft 105 is provided with an eccentric in the bearing formed in the bracket 106, the said eccentric as indicated by dotted lines at 107 in Fig. 6 so that by turning the said shaft the eccentric will cause the shaft to move the worm 104 into and out of mesh with the gear 103. The outer end of said shaft 105 is provided with a double pulley 108 which is adapted to be connected by a suitable belt 109 with a double pulley 110 fastened upon one end of the shaft 56. The belt 109 is usually kept somewhat slack so that it can be removed from the pulley 110 and crossed for reversing the feed when desired. The slackness of 65 the belt is taken up by a pulley 111 carried by a lever 112, one end of which is journaled upon the shaft 105 while the other end is drawn toward the belt by a spring 113. It will be understood of course that said belt 109 may be shifted from one part of each 70 double pulley to the other in accordance with the speed the feed mechanism is to be driven.

The shaft 56 is usually driven by a sprocket chain 114 which passes around a 75 sprocket wheel 115 secured to said shaft 56, and a sprocket secured to a pulley 116. The said pulley 116 is carried by the bifurcated ends of a spacing rod 117, the other end of said rod being also bifurcated to accommodate the sprocket wheel 115 and journaled upon the shaft 56. The pulley 116 is driven by any suitable belt 118, which extends to any suitable source of power not shown. By this mechanism power may be communicated to said shaft 56 for operating the worms 55 and 104, no matter to what position on the carrier bars 11, the carriage 12 may be shifted for reaching and grinding any one of the cylinders of an engine. 90

A similar yielding feed mechanism must also be employed in driving the pulley 75 of the tool carrying mandrel. Thus a belt 119 may extend from the said pulley 73 to a pulley 120 carried by a spacing bar or rod 121, the said pulley 120 usually being a double pulley, so that another belt 122 may extend therefrom to a double pulley 123. The pulley 123 receives its movement from a belt 124 which extends to any suitable 100 source of power not shown. The weight of the spacing rod 121 and the pulley 120 will keep the belt 119 taut at all times so that notwithstanding the gyratory eccentric movement of the tool carrying mandrel, the 105 said pulley 73 will be constantly rotated. The belt connection just described also permits the placing of the carriage 12 over any of the cylinders that are to be ground or bored in the same manner as described with 110 respect to the belting and sprocket chain for driving the shaft 56.

The portable character of the invention is not only of advantage in that it can be moved about from one cylinder of an engine 115 to another, but also because the device can be readily placed in any ordinary lathe and adjusted for horizontal or inclined use. Thus as shown in Fig. 9 the carriage 12 may be mounted upon bars 125 bolted or otherwise secured upon the tool carriage 126 of a lathe 127. By turning the casing 40 to a horizontal position as shown in said Fig. 9, a grinding tool as 128 may be caused to grind the interior of any article as 129 which may be secured to the usual face plate 130 of the lathe. In using the device in the lathe the tool mandrel is usually brought to the central concentric position within the outer mandrel and the outer mandrel need not be 130

operated, the inner one only being rotated by belting 131, for turning the grinding tool 128. The article ground will usually be turned by the rotation of the face plate 130 of the lathe, in the usual way. As indicated in dotted lines also the casing 40 may be tipped upon its trunnions 43 to any desired angle according to the surface or article upon which the grinding or boring tool is to be operated. The great adaptability of the mechanism of this invention to various kinds of work will thus be evident.

While the boring tools of any kind can be applied to either mandrel, where it is necessary to take off a greater portion of material, than is generally removed by the ordinary grinding tool, it is preferable to employ a simple tool holder like that shown in Fig. 11 of the drawing. The said tool holder 132 is made hollow and provided with a screw threaded opening 133 of a proper diameter to slip over the oil collecting cup 82 and engage the threads upon the lower end of the outer mandrel 53, the device being screwed up tightly against the ring nut 59 which holds the mandrel 53 within the bearing member 51. The tool holder 132 is also provided with a transverse tool socket 134 in which any boring tool 135 may be placed. A set screw 136 is provided for clamping the tool in said socket. When it is found that a grinding tool will not take off sufficient surface to properly finish the interior of a cylinder, it is only necessary to remove the grinding tool and screw the tool holder 132 upon the outer mandrel 53, in order to permit the employment of a boring tool to make any desired cut upon the inner surface of the cylinder or other article. Of course in this instance it is not necessary to drive the inner mandrel at all and the belt 119 is not placed upon the pulley at that time.

The bearing member 51 is normally held fast in the casing 40 by clamping bolts 137 applied at the split end portions of the said casing 40 for drawing the ends of the casing tightly upon said member. By unscrewing the said clamping bolts, the bearing member 51 carrying both of the mandrels may be readily removed at any time for the examination of the parts and for cleaning or repairing and adjusting the same if found needful.

The operation of the various portions of the device will be readily understood in connection with the above description. In using the mechanism on an ordinary automobile engine for example, the device upon the base plate 10 is rested upon the open ends of the cylinders of the engine as indicated in Fig. 1, said plate being bolted thereon in any desired manner. The carriage is slipped along the bars 11 until approximately in position over the cylinder to be ground. A grinding

tool is then placed in the mandrel, and the feed screw 100 operated to lower the carriage until the said tool projects into the cylinder. By the application of a squared rod or key to the socket 88 of the shaft or rod 87, the eccentric position of the mandrel is adjusted in accordance with the radius of the cylinder, so that the grinding tool should just touch the surface of the cylinder when the outer mandrel 53 is given a complete turn. By turning the mandrel and moving the grinding tool around within the cylinder the carriage can be quickly and accurately centered over said cylinder. The diamond which is carried by the bridging portion of the carriage is then set so that its cutting point or edge will be the desired radial distance from the center of the cylinder to cause the grinding tool when just touching the same, to grind the cylinder to the required diameter. The cylinder is usually increased in diameter by the grinding operation, just enough to true up the cylinder from end to end and when the diamond is once set, it does not have to be changed for two or more cylinders of the same engine. When the grinding tool is set eccentrically so that it will just touch the diamond sufficiently to have its grinding surface renewed by turning against the said diamond, the said tool will after passing the diamond and being slightly reduced thereby, grind the cylinder to the exact size desired. In shifting the carrier to succeeding cylinders, the diamond is not changed in its adjustment and when the grinding tool will just pass the diamond, having its grinding edge freshened thereby, each succeeding cylinder will be absolutely the same diameter as the preceding one or ones. This accurate result is not as possible with devices in which the cylinder to be ground is moved with respect to the grinding tool, in accordance with the common method heretofore in use for it is very difficult to readjust successive cylinders with respect to a grinding tool so that they will occupy exactly the same relation to the tool as the preceding cylinder. With the present invention in which the diamond after once set, needs no readjustment for successive cylinders, a grinding tool which will just pass the diamond, engaging it sufficiently to have a little of its periphery removed, will of necessity produce a cylinder of the same diameter in every case.

It will be observed that in the device embodying this invention also that the change from a grinding tool to a boring tool and vice versa may be readily made without disturbing the adjustment of the mandrels. Thus when more material must be taken from some of the cylinders of an engine than can be well removed by a grinding tool, the grinding tool is removed from its mandrel and the tool carrying member 132 is

screwed into place at the lower end of the mandrel 53, and the cylinder is first bored to give it the desired diameter. It is only necessary then to remove the member 132 and place a grinding tool in the inner mandrel in order to finish off any slight unevenness in the cylinder that may be left by the grinding tool.

In connection with the outer mandrel 53 and the adjustable sleeve 62 within it, means is preferably provided after the said sleeve has been adjusted to a proper eccentric position to clamp the sleeve firmly therein. This is generally accomplished by placing a nut 138 on the lower threaded portion of the sleeve 62 so as to bear against the lower end of the mandrel 53 and another nut 139 is applied to the upper threaded screw portion of the said sleeve 62 so as to bear against the upper end of the said outer mandrel 53. When adjusting the sleeve it is usually only necessary to loosen one of said nuts, say, the upper one 139, and after the sleeve has been moved to its proper eccentric position in the mandrel 53 to tighten the said nut for firmly holding it in place in said mandrel.

It will be understood that when the carriage 12 is to be moved along the bars 11 and centered successively over the different cylinders of a multiple cylinder engine, for grinding them, that the collars 30 and 31 with their micrometer rings 32 and 33, are very useful in obtaining a fine adjustment 35 of the carriage over each particular cylinder.

It will be evident also, that many of the minor details of construction may be considerably varied and mechanical equivalents substituted therefore if desired, all 40 within the spirit and scope of the invention.

What is claimed is:

1. A portable grinding mechanism comprising a base having elongated guide ways mounted thereon and adapted to be clamped upon an article to be ground, and a tool operating mechanism traveling upon said guide ways and adapted to be adjusted over one or more articles to be ground.

2. A portable grinding mechanism comprising a work engaging base, adapted to extend over articles to be ground and having longitudinally extending carrier bars, means for rotating a grinding implement, said means being adjustable on said carrier bars, whereby it will be caused to operate upon one article to be ground after another, and means for imparting a gyratory movement to the implement, whereby it will be brought into contact with every part of the 60 surface of the article to be ground.

3. A portable grinding mechanism comprising a work engaging base, an adjustable carriage movable over said base, a tool carrying mandrel journaled upon said carriage 65 whereby the tool may be directed in any de-

sired manner, means for giving the tool carrying mandrel an eccentric action on the carriage for carrying the grinding tool over every part of the surface to be ground, and means for allowing said tool to move in a direction parallel with the center line of said mandrel.

4. A portable grinding mechanism having a double mandrel mechanism, one being within the other, means for imparting movement to each portion of said double mandrel mechanism for carrying a grinding tool properly over the surface to be ground, and means for holding the said mandrel mechanism at any desired angle with respect to the work.

5. A grinding mechanism having a tool rotating mandrel and an inner tool shifting mandrel, means for rotating the tool mandrel, independent means for operating the tool shifting mandrel, and carrying means for the mandrel mechanism adapted to hold the tool at any desired angle to the work.

6. A grinding mechanism comprising a carriage, a rotary mandrel having a radial recess therein, a tool mandrel, a mechanism for adjusting said tool mandrel in said recess and giving it an eccentric throw, and means for rotating the tool carrying mandrel.

7. A grinding mechanism comprising a rotating mandrel having a radial guide way therein, a tool driving mandrel mounted therein and capable of adjustment in said guide way with respect to the axis of the 100 said rotating mandrel and means for adjusting the tool driving mandrel from a concentric position to eccentric positions in said rotating mandrel.

8. A grinding mechanism having an outer 105 mandrel and an inner mandrel, the outer mandrel having radially arranged guide ways therein, means for adjusting the inner mandrel in said radial guide ways with respect to the outer mandrel and independent 110 means for rotating each mandrel.

9. A grinding mechanism comprising a support adapted to be secured to articles to be ground, a carriage adjustably mounted thereon and movable transversely to the 115 axis of the article to be ground, means for setting the said carriage with respect to the surface to be ground and a mandrel mechanism mounted upon said carriage for operating a grinding tool.

10. A cylinder grinding mechanism having adjustable carrier bars whereby the carriage may be moved over a plurality of cylinders, a carriage adjustable upon said bars and a tool driving mechanism mounted upon 125 said carriage.

11. A grinding mechanism comprising a base having guide ways thereon, a carriage projecting upwardly upon said guide ways and having members traveling thereon, 130

- guiding upright members and means for adjusting the position of said upright members upon the said carriage.
12. A cylinder grinding mechanism comprising elongated guides adapted to extend over the ends of a plurality of cylinders, upright guides on said first mentioned guides, a mandrel mechanism mounted in said upright guides, and means for actuating the mandrel mechanism.
13. A cylinder grinding mechanism having a base, guide bars thereon adapted to extend over a plurality of cylinders, a carriage having foot portions adapted to slide upon said guide bars for bringing the mechanism over any desired cylinder, a mandrel mounted in the said carriage and means for actuating the mandrel to drive a grinding tool within any cylinder over which the carriage may be disposed.
14. A cylinder grinding mechanism comprising a base, parallel guide bars adjustably mounted on said base, and adapted to extend opposite a number of cylinders to be ground, upright standards adjustably movable on said bars for positioning the grinding mechanism over the cylinder desired, a mandrel mechanism journaled upon said standards, an inner tool carrying mandrel in said journaled mandrel and means for driving the tool mandrel, the structure of the mechanism being such that a plurality of cylinders may be ground to exactly the same diameter.
15. A cylinder grinding machine comprising an elongated guide mechanism adapted to extend across the ends of a plurality of cylinders, an upright carriage having standards and sleeves at the lower ends thereof adapted to move on said guide way, vertically moving sleeves on said standards, a mandrel mounted within said standards and having journals interposed between the same and said vertically moving sleeves, whereby the mandrel may be set at any desired angle between the standards, means for automatically raising and lowering the said sleeves on said standards for advancing a grinding tool within a cylinder to be ground, a tool carrying mandrel revolvably mounted within the outer mandrel and adapted to carry a tool below the guide base whereby it may be caused to grind any of the cylinders over which the mechanism may be placed.
16. A portable cylinder grinding mechanism having an adjustable carrier adapted to be positioned with respect to a cylinder to be ground, an outer mandrel journaled upon said carrier, and having laterally extending guide ways, inner mandrel adjustably mounted with respect to the axis of the said outer mandrel in said guide ways, means for adjusting the inner mandrel to different degrees of eccentricity with respect to the axis of said outer mandrel, and means for moving the mandrels longitudinally of the cylinder to bring the grinding tool into contact with every portion of its inner surface.
17. A grinding mechanism comprising a boring or grinding tool, a mandrel mechanism for actuating the said tool, a vertically moving carriage carrying said mandrel mechanism, a horizontally moving carriage supporting said vertically moving carriage adapted to move over a number of adjacent cylinders and means for adjusting the horizontally moving carriage with respect to the cylinder to be ground.
18. A grinding mechanism comprising an adjustable carriage adapted to be held with respect to a plurality of articles to be ground, mandrels movably mounted on said carriage whereby the mandrels may be set at any desired angle with respect to the work and means for actuating the said mandrels for causing a grinding tool to act upon a given surface.
19. A grinding mechanism having an elongated guide way, an adjustable carriage adapted to be moved longitudinally of said guide way and to be held with respect to a plurality of articles to be ground, a secondary carriage journaled on the first mentioned carriage and adapted to be adjusted at an angle with respect thereto, a boring mechanism carried by the secondary carriage and means for feeding the secondary carriage upon the first carriage for causing the boring tool to engage every part of the given surface.
20. A grinding mechanism having an outer mandrel adapted to carry the arbor of a grinding tool, a sleeve adjustably mounted in said mandrel and adapted to receive the arbor of the tool, screws for moving the said sleeve to different parallel positions with respect to the axis of the mandrel, gearing for operating the said screws, a shaft for actuating the said gearing and a tool carrying arbor journaled in said sleeve.
21. A cylinder grinding mechanism comprising a support adapted to be adjustably held with respect to a cylinder, a hollow mandrel mounted upon said support and having radiating guide openings in the end portions thereof, a hollow sleeve mounted within the said guide openings, means for adjusting the sleeve to eccentric positions in the mandrel, a tool carrying mandrel journaled in said sleeve, means for rotating said latter mandrel, and means for rotating said former hollow mandrel for carrying the rotating tool entirely around the inner surface of the cylinder.
22. A cylinder grinding mechanism comprising an adjustable support adapted to be fastened to a cylinder, an outer mandrel having radiating guide ways in the ends thereof, a sleeve extending through said guide ways, pairs of adjusting screws ar-

ranged near each end of said mandrel, gears carried by each screw, worms interposed between the gears at each end of the mandrel, a shaft connecting said worms and adapted 5 to turn the same simultaneously for adjusting the pairs of screws at each end of the mandrel simultaneously for setting the sleeve with respect to the axis of the mandrel and in parallel relation therewith, a 10 hollow mandrel journaled in said sleeve and having a tapered socket therein for receiving the shank of a tool, a draw rod for fastening the shank of a tool in said socket, a pulley adapted to turn the said mandrel, 15 and means for turning the outer mandrel, the relative actions of the two mandrels operating to move a tool entirely around the inner surface of the cylinder to be ground.

23. A grinding mechanism comprising an 20 adjustable carriage having a pivotally mounted casing, means for clamping the casing in any desired position upon its pivot points, a bearing member fitted in said casing, a hollow mandrel journaled in said 25 bearing member and having a gear secured thereto, a worm meshing the said gear, means for driving said worm for actuating said gear and turning the mandrel, a tool carrying mandrel mounted within the said 30 hollow mandrel, means for rotating the said tool carrying mandrel independently of the other mandrel, and means for advancing the said casing toward the work whereby a 35 gyroscopic action may be imparted to a tool for affecting every part of the work.

24. A grinding mechanism having a carriage adjustable toward and away from an article to be operated upon, a tool operating

mandrel mechanism having a worm gear, a worm meshing therewith for turning the 40 mandrel mechanism, a shaft for actuating the said worm, a feed screw adapted to advance the carriage toward the work, a gear for turning the said feed screw, a worm meshing therewith, and means for driving 45 said worm when the first mentioned worm is driving the mandrel mechanism whereby the grinding tool will be advanced over the surface of the work as it affects the same.

25. A grinding mechanism having a support, sleeves adjustable upon said support and having oppositely arranged bearings thereon, a casing movable on said bearings whereby it may be set at any angle thereto, means for holding the casing in its adjusted 50 positions, a mandrel mechanism carried by said casing, having an inner tool carrying mandrel and an outer tool gyrating mandrel, means for holding the tool carrying mandrel in eccentric relation to the other 55 mandrel, a yielding driving means for rotating the tool carrying mandrel, said means being capable of accommodating itself to the eccentric action of said tool carrying mandrel, and yielding driving means for 60 the tool gyrating mandrel adapted to accommodate itself to the adjustment of the grinding mechanism over any part of the article operated upon.

In testimony whereof, I have hereunto set 70 my hand, in presence of two witnesses.

EDWARD W. CLARK.
